Primary Examiner—Wallace R. Burke*Assistant Examiner*—Joel Sincavage*Attorney, Agent, or Firm*—Hugh D. Jaeger**[57] CLAIM**

The ornamental design for battery housing for a portable radio telephone, as shown.

DESCRIPTION

FIG. 1 illustrates a perspective view of battery housing for a portable radio telephone our new design;

FIG. 2 illustrates a front view thereof;

FIG. 3 illustrates a right side view thereof;

FIG. 4 illustrates a left side view thereof;

FIG. 5 illustrates a top view thereof;

FIG. 6 illustrates a bottom view thereof; and,

FIG. 7 illustrates a back view thereof.

FIG. 1

FIG. 2

FIG. 3

FIG. 4

FIG. 5

FIG. 6

FIG. 7
